UNITED STATES PATENT OFFICE.

CHARLES M. OTIS, OF ROCHESTER, NEW YORK, AND FORREST J. COUCH, OF CINCINNATI, OHIO, ASSIGNORS TO THE AMERICAN LAUNDRY MACHINERY COMPANY, OF NORWOOD STATION, CINCINNATI, OHIO, A CORPORATION OF OHIO.

SAFETY DEVICE FOR OVERDRIVEN EXTRACTORS.

Application filed October 9, 1926. Serial No. 140,573.

This invention relates to centrifugal extractors such as are employed in laundries for the purpose of removing the bulk of the water from washed clothes, and has special reference to the provision in such a machine of features rendering the same operable with safety regardless of carelessness in the manipulation thereof.

More particularly the invention relates to means whereby the starting of the machine is impossible until after the usual safety door has been closed, and likewise the door may not be reopened until the moving parts of the machine are at rest.

Specifically the objects of the invention are to provide for the above purpose a mechanical interlock between the door latch and the control mechanism of the machine, which shall be simple, certain in operation, "fool proof", and withal inexpensive of manufacture. The exact nature of the invention, together with its advantages, will be apparent from the following description taken in connection with the accompanying drawings in which Fig. 1 is a front elevation of an overdriven extractor arranged for belt drive and embodying my invention, parts being broken away and parts in section to more clearly show the construction thereof. Fig. 2 is a side elevation of the lower portion of the machine. Fig. 3 is a detail in elevation of the machine. Fig. 4, a horizontal section in the plane of lines 4—4 of Figs. 1, 2, and 3. Fig. 5 is a detail section in the plane of line 5—5 of Figs. 1, 2, and 3, the position of the mechanism being shown in that corresponding with the extractor basket idle and the control lever latched in the off position. Fig. 6 is a detail similar to that of Fig. 5 showing the control lever in off position of the driving mechanism but with the extractor door latched closed. Fig. 7 is a horizontal section in the plane of lines 7—7 of Figs. 1, 2, 3, and 12. Fig. 8 is a detailed side view of the door counterbalancing mechanism with parts broken away to show

construction. Fig. 9 is a horizontal section of a centrifugal latching device employed, taken in the plane of line 9—9 of Fig. 1. Figs. 10 and 11 are similar details in the planes of line 10—10 and 11—11 respectively of Figs. 1 and 12. Fig. 12 is a detailed section in the plane of line 12—12 of Figs. 1, 9, 10, and 11 with certain parts broken away. Fig. 13 is a detail of the brake mechanism.

In the drawings 1 indicates the base of the machine, forming with the uprights 2 and supporting bracket 3, the stationary frame of the machine. Suspended from the bracket 3 by means of a swivel mechanism 4 and arms 5 is a curb 6, in the lower central portion of which is a bearing 7 for the spindle 8 upon which is mounted for rotation therewith a basket 9 having foraminous walls.

Fixed upon the spindle 8 is a pulley 10 whereby the basket may be driven through the belt 11 by the drive pulley 12, the belt running over idler pulleys 13 and 14 as indicated. The pulley 12 is fixed on the shaft 15 upon which is also secured a fast pulley 16 and corresponding therewith a loose pulley 17, a continuously driven belt 18 being movable to run over either of the pulleys 16 and 17 to drive or release the extractor basket, movement of the belt 18 being controlled by a pair of arms 20 mounted on a belt shifter rod 19 slidable in bearings 21. The end of the belt shifter rod carries a clevis 22 in connection with lever 23 fastened upon the rock shaft 24 upon the forward end of which is mounted a handled control lever 25. It will be obvious that movement of the handle of the lever 25 to the right, Fig. 7, will position the belt 18 upon the tight pulley 16 to drive the extractor; and movement of the handle to the left will effect a transfer of the driving belt to the loose pulley 17, releasing the drive from the machine.

A brake shoe 28 is mounted as indicated in Fig. 13 upon the lever 27 and operable by the hand wheel 26 to engage the face of the pulley 10 to quickly bring the basket to

rest upon disconnection of the driving means therefrom.

At the front of the machine is provided a cover or door 29 provided with outwardly extending arms 30 upon which are mounted rollers 31 engaging vertical tracks 32 on which the door may be raised to afford access to the open mouth of the basket, or lowered to guard the basket, the door being counterbalanced to its upper position by weights 35 suspended from chains 36 running over pulleys above the door as indicated. The arm 33 upon the door enters, in the lowered position thereof, a latch box 34 and is engageable 10 in this position by the notch of a latch member 53 pivotally mounted within the latch box as indicated in Fig. 3.

Secure with the spindle 8 is a member 37 provided with a pair of outwardly extending arms 37^a the ends of which project downwards. Splined upon the hub of the member 38 is a member 38 provided with arms extending beneath the arms 37^a, the arms of the member 38 terminating in arcuate cup shaped 25 depressions each forming a race 38^a for a ball 39. The formation of the ball races is such that upon appreciable rotation of the spindle 8 the balls will be thrown to the position indicated in Figs. 9, 10, and 11 by centrifugal 30 action, the bottoms of the races however being so inclined that the balls will move to the lower portion 38^b of the races as the spindle ceases to rotate. The downwardly projecting ends of the arms 37^a extend only partially 35 over the ball races 38^a, the arrangement being such that when the spindle is substantially in a state of rest, arms 37^a will be cleared by the balls to allow full upward movement of the member 38; but upon appreciable rotation of 40 the spindle, the balls will move upward and outward in their races to form a positive stop between the members 37^a and 38^a to prevent any upward movement of the member 38, a collar 40 fast upon the hub of the member 37 limiting downward motion of the member 38.

As well shown in Figs. 11 and 12, the arcuate cup-shaped depressions or races 38^a not only have bottoms sloping downwardly and inwardly toward the axis, but the curve of the depressions is such that they extend from points beneath the abutments or downwardly extending ends of member 37^a inwardly toward the axis and forwardly in the direction of rotation of the spindle and basket, which 55 is clockwise in Fig. 11. The slightest rotation of the basket therefore not only throws them outwardly, but causes them to travel around the curve into the pocketed ends of the depressions, where they are held, not only 60 by the effect of centrifugal force, but also by the momentum effect of the basket, in such manner that their tendency to return to the inner or non-obstructing position is so slight and is resisted by such preponderant forces 65 that the rotational speed of the basket must

be very materially reduced and almost if not actually, at zero speed before the balls travel inwardly.

Adapted to bear upon the faced surface 41 of member 38 is a pair of shoes 42 carried by a yoke 43 fixed upon the rock shaft 44 which is suitably mounted in the frame as indicated. A lever 47 provided with an extended abutment surface is fixed upon the end of the rock shaft, and a lever 49 terminating in a spherical head as at 48 is fixed upon a rock shaft 50, whereby motion of the rock shaft 44 to move its abutment surface 47 upwards is converted into clockwise motion (Figs. 1 and 3) of the rock shaft 50. Upon the near end of rock shaft 50 (Figs. 1 and 3) is a lever 52 projecting through a slot in the latch box 34 and carrying on its end a finger 52^a extending into the plane of the latch 53.

By the mechanism described it will be obvious that the weight of the member 38 is transmitted to the member 53 to urge the latch in a counter-clockwise direction (Figs. 1 and 3); and that when the balls 39 are caused by rotation of the spindle to assume a position beneath the arms 37^a, the lug 53 will be positively prevented from movement from the position shown in Fig. 1 to that shown in Fig. 3; that is, provided the door 29 has been lowered to closed position its opening will be positively prevented during any appreciable rotational velocity of the basket 9.

Extending downwards from the pivot of the latch 53 is a lever arm 53^a. Upon the control lever 25 is a lug 55 extending through a slot 56 in the latch box cover into the plane of the arm 53^a, whereby completion of the movement of the control lever to the off position will effect release of the latch from the door, which will thereupon rise; but such movement will be prevented by the centrifugal mechanism described during motion of the basket, although movement of the control lever merely to a position in which the lug 55 abuts the lever 53^a is sufficient to complete 110 shifting of the belt 18 onto the idle pulley 17.

In the cover of the latch box are mounted for longitudinal movement the push buttons or pins 61 and 64 backed by a lever 60 whereby depression of either of the push buttons will effect projection of the other button outwards. A spring pressed ball 62 is arranged to co-operate with depressions in the lever 60 to retain the same, and therefore the push buttons, in either of the positions indicated in Figs. 5 and 6. The push button 64 is so positioned as to prevent, when projecting outwards as in Fig. 6, the control lever 25 affecting the latch 53; and the push button 61 is positioned so that after depression of the button 64 and release of the door, the button 61 will prevent movement of the control lever to throw the belt 18 upon the driving pulley 16. Hence movement of the control lever from the fully off position to the on po- 130

sition is subject to depression of the push button 61.

- Pivotaly mounted at 58 is a bell crank locking lever 57 urged by the spring 59 to a position in which its lower arm 57^a abuts the end of the lever 60 in alignment with the push button 61, as indicated in Fig. 5, whereby depression of the push button 61 to clear the control lever is normally positively prevented.
- 10 The opposite arm of the bell crank 57, however, is engageable by a bent extremity of the member 33 upon the door, in closed position of the door, to move the bell crank to the position indicated in Fig. 3 wherein the arm 57^a 75 assumes the position indicated in Fig. 6, clearing the push button which may then be depressed as shown in Fig. 6 and the control lever thereupon moved to on position.

From the above description it is obvious that 20 opening of the door is positively prevented at all times except when the basket is substantially at rest; and movement of the control lever to on position is positively prevented pending prior closing of the door.

25 Operation of the machine will therefore be as follows, assuming the machine idle, the door opened and the control lever and latch mechanism in position as indicated in Fig. 5.

To start the machine it is first necessary 30 that the door be lowered to closed position whereupon it is immediately latched by the action of the member 52 upon the latch 53 as described, this action being sufficient to move the control lever from the fully off position to that of Fig. 5 if necessary. Movement of the control lever beyond the position of Fig. 5, that is, sufficient to move the belt 18 to start the spindle, is prevented by the button 61. The door being now closed and 40 the lever arm 57^a being consequently in a position (Fig. 6) clear of the lever 60 the operator may press the push button and start the machine by throwing the control lever to the right. As the basket starts to rotate the balls 45 39 move outwards in their races to positively prevent release of the door by the latch 53.

To stop the machine the operator moves the control lever 25 to the left, this movement being limited however by the push button 64 which is now projecting outwards from the 50 latch box into the plane of the lever as indicated in Fig. 6. This limited motion of the control lever is sufficient to disengage the driving belt from the driving pulley but not 55 sufficient to cause engagement of the lug 55 on the control lever to release the latch which is also still positively maintained in the door secured position by the centrifugal mechanism described. The operator next applies 60 the brake 26 whereupon, assuming that the basket is brought to rest, the button 64 is next depressed and the control lever moved to the extreme left or latch release position 65 releasing the latch from the door which thereupon rises. Upon release of the control lever

it is moved again to the position as in Fig. 5 by the action of the lever arm 52 acting through the latch member 53 with its lower member 53^a; further movement of the control member being prevented again by the push button 61 (Fig. 5).

What we claim is:

1. In an article of the class described a frame, a container mounted for rotation therein, a movable door adapted to guard the mouth of said container, driving means for rotating said container, a lever controlling said driving means, latch means for securing said door in guarding position, a device responsive to rotation of said container, a connection between said latch means and said device whereby the weight of a part of the device tends at all times to maintain said latch means in door securing position and positively maintains said latch member in 85 said position during rotation of said container, and said lever being provided with means to release the latch means upon movement of said lever from driving position beyond its driving release position. 90

2. An extractor, comprising a frame, a rotatable basket therein, driving means for said basket, a guarding door for said basket having open and closed positions, means for latching said door in closed position, and a 95 movable actuator having three positions, to wit, "on", "off", and "latch release", connections between said actuator and said driving and latching means whereby movement of the actuator to the "on" and "off" position starts 100 or stops the basket and movement of the actuator to the "latch release" position releases said latching means.

3. An extractor of the type described in claim 2, provided with a movable abutment 105 obstructing or preventing movement of the actuator back and forth between "on" and "off" positions, and with door operated means controlling movement of said abutment.

4. An extractor of the kind described in claim 2, including means governed by rotation of the basket for preventing movement of said actuator from "off" position to "latch release" position unless the rotational speed has been safely reduced. 110

5. An extractor of the kind described in claim 2, including door actuated means for preventing movement of said actuator from "off" to "on" position unless the door is latched, and means governed by rotation of 120 the basket for preventing movement of the actuator from "off" to "latch release" position unless said rotational speed has been safely reduced.

6. An extractor, comprising a frame, a rotatable shaft and basket therein, a guarding door for the basket movable to open and closed positions, door latching means, and controlling mechanism therefor including two members rotatable with the spindle and 125 130

connected for relative movement along the spindle axis, the upper member having abutments and the lower member having pockets containing balls, said pockets having sloping bottoms and extending from a point beneath said abutments inwardly toward the axis and forwardly in the direction of rotation to a point out of registration with said

abutments, and connecting means between said members and said door latching means 10 for controlling the latter.

In testimony whereof we hereby affix our signatures.

CHARLES M. OTIS.
FORREST J. COUCH.
